UNITED STATES PATENT OFFICE.

PAUL E. SUTRO, OF PHILADELPHIA, PENNSYLVANIA.

DESIGN FOR HALF-HOSE.

SPECIFICATION forming part of Design No. 32,603, dated April 24, 1900.

Application filed November 7, 1899. Serial No. 736,196. Term of patent 7 years.

To all whom it may concern:

Be it known that I, PAUL E. SUTRO, a citizen of the United States, residing in Philadelphia, Pennsylvania, have invented a new and original Design for Half-Hose, of which the following is a specification.

My design for half-hose is fully shown in the accompanying drawing, which represents a side view of the same.

10 The essential features of the design are the plain foot, the uniformly-ribbed top, and the body in which plain rib-wales alternate with tuck rib-wales.

15 In the drawing, 1 represents the plain foot, the term "foot" including the heel and the term "plain" in this connection meaning an unribbed fabric.

2 represents the uniformly-ribbed top, and 3 the body, the plain rib-wales being shown at 4 and the tuck rib-wales at 5.

Having thus described my invention, I claim and desire to secure by Letters Patent—

20 The design for half-hose, substantially as described and as shown in the accompanying drawing.

25 In testimony whereof I have signed my name to this specification in the presence of two subscribing witnesses.

PAUL E. SUTRO.

Witnesses:

F. E. BECHTOLD,
JOS. H. KLEIN.
